UNITED STATES PATENT OFFICE.

JOSE E. QUE, OF MANILA, PHILIPPINE ISLANDS.

TRAFFIC SIGNAL.

Application filed February 17, 1925. Serial No. 9,797.

The present invention provides a signal for motor vehicles whereby the driver may signal his intention when about to turn to the right or to the left, or to bring the vehicle to a stop so that the driver of a vehicle in the rear may act accordingly and thereby avoid a fatality and obviate confusion, said signal being of such construction as to insure its clear observation in daylight or 10 after dark.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a front view of a signal embodying the invention,

Figure 2 is a side view of the signal,

Figure 3 is an elevational view of the signal having the front omitted and showing the parts on a larger scale,

Figure 4 is an enlarged sectional view on the line 4—4 of Figure 1,

Figure 5 is an enlarged sectional view on the line 5—5 of Figure 1,

Figure 6 is an elevational view of the front,

Figure 7 is a plan view of the switch,

Figure 8 is a sectional view of the switch on the line 8—8 of Figure 7,

Figure 9 is a sectional view on the line 9—9 of Figure 7,

Figure 10 is a sectional view on the line 10—10 of Figure 8, and

Figure 11 is a diagrammatic view of the circuits.

Corresponding and like parts are referred to in the following description and designated in the several views of the drawings by like reference characters.

The signal comprises a lantern or casing having the outline of a cross, and disposed with two of the arms in horizontal position and the other two in vertical position, the several arms being of equal length and this cruciform casing 1 is subdivided by a vertical partition 2 to form front and rear chambers, the rear chamber containing the wiring and the front chamber receiving the

electric bulbs and the directional indicating means such as arrows, one of the arrows being disposed vertically and adapted to indicate "stop" and the other two arrows being reversely disposed in horizontal position to indicate a turn to the right or to the left, the several arrows crossing and the reversely disposed horizontal arrows overlapping, the selected arrow being illuminated when displayed to clearly distinguish it from the other two arrows which are not illuminated thereby avoiding confusion. The back 3 is bolted or otherwise secured to the rear of

the casing 1 and the front is closed by a transparent plate 4 which is held in place by means of a rim 5 which is bolted or otherwise secured to the front of the casing, and by having the front and the back removable access may be readily had to the interior of the casing for any required purpose. The partition 2 has openings formed therein to which sockets 6 are clamped or otherwise secured to receive electric bulbs 7 which are included in different circuits controlled by a multiple switch conveniently disposed for ready operation by the driver

whereby a signal may be displayed when the vehicle is about to be turned either to the right or to the left or to be brought to a stop.

The front chamber of the casing is subdivided into compartments designated by the numerals 8, 9, 10, 11, 12, 13 and 14, each receiving an electric bulb and each being closed at the front by the transparent plate 4 which is preferably of amber color and smooth upon its inner side and waved upon its other side. The center compartment 8 is of square formation, the upper compartment 11 and the lower compartment 12 conform approximately to the arms of the casing whereas the compartments 9 and 10 are pointed and are located within the respective horizontal compartments 13 and 14, with their top and bottom walls sloping inwardly and rearwardly, as indicated most clearly in Figure 5, the points of the compartments 9 and 10 being disposed in front of the electric bulbs 7 located in the compartments 13 and 14. By having the top and bottom walls of the compartments 9 and 10 sloping inwardly and rearwardly, the formation of shadows is wholly obviated when the bulbs are lighted, and this is essential to the clear outlining of the indicating means which as stated, consists of

arrows so that the direction of turn may be clearly indicated without any possible confusion or uncertainty.

The transparent front 4 is covered upon the rear side so as to clearly outline three crossing arrows, the one being disposed vertically and the other two in overlapping horizontal position, the one being arranged in reverse position to the other, and the light 10 and the compartments are so disposed as to clearly indicate one of the arrows at a time to the exclusion of the others and when the light is burning in either of the pointed compartments 9 or 10, the light in the corresponding compartments 13 and 14 is not burning so that such compartments are in darkness thereby insuring one or the other points 9 or 10 being clearly defined, however, when the point 9 is illuminated, the 20 compartments 8, 10 and 14 are simultaneously lighted, thereby displaying the arrow pointing to the left so as to indicate a left turn, and at this time, the compartments 13, 11 and 12 remain in darkness. When the 25 signal is set to indicate a right turn, the compartments 10, 8, 9 and 13 are lighted and the compartments 14, 11 and 12 remain in darkness so as to clearly outline the arrow pointing to the right. To signal a stop, the 30 compartments 11, 8 and 12 are illuminated, the remaining compartments 9, 13, 10 and 14 remaining in darkness so that the vertically disposed arrow is clearly outlined. The compartment 8 is located at the crossing 35 of the three arrows and is illuminated when either one of the three arrows is lighted.

Referring to Figure 11, the same shows a diagram of circuits including the several 40 lights, said circuits being controlled by means of a multiple switch which is shown in detail in Figures 8, 9, and 10, and which comprises a base 15, a casing 16 and a cover 17 in which is formed a horizontal slot 18 45 and a vertical slot 19, the latter communicating with the slot 18 at a point intermedi-

ate its ends. A switch member 20 is connected with the base 15 by means of a universal joint 21^a and is normally maintained in neutral position by means of springs 21 50 attached to the base and exerting a lateral pressure upon the member 20. The switch member 20 projects through the cover 17 and is adapted to operate in the slot 18 and 19 and when moved to the end of the slot 55 19, the vertical arrow is displayed and when moved to the left of the slot 18, the horizontal arrow pointing to the left is displayed, thereby indicating a left turn and when moved to the right hand end of the slot 18 the horizontal arrow pointing to the right is displayed thereby indicating a right hand turn. The switch member 20 is provided with contacts 22 which are adapted to coat with complementary contacts 23 at 60 the sides of the casing 16 whereby to close the proper circuit indicated in a diagram Figure 11 to insure proper display of the required signal. The numeral 24 denotes a battery or source of electric supply, and 25 70 the several lead wires running to the electric lamp 7.

What is claimed is:—

A vehicle signal, comprising a cruciform casing, a transparent plate closing the front 75 of the casing and having portions rendered opaque, the transparent portions delineating signal devices disposed to cross, a smaller rectangular compartment arranged in the middle of the casing, partitions extending 80 from the corner walls of the smaller compartment to the inner corners of the cruciform casing forming a compartment in each arm thereof, and another compartment in each horizontal arm of the cruciform casing 85 having a pointed end pointing outwardly of the arm and having its inner walls inclined from the pointed end inwardly of the arm and rearwardly.

In testimony whereof I affix my signature.

JOSE E. QUE.
